[57] **CLAIM**

The ornamental design for a housing for a data processing component, as shown and described.

DESCRIPTION

FIG. 1 is a perspective view from the front, top and left side of a housing for data processing component showing our new design;

FIG. 2 is a view from the front of a housing for data processing component shown in FIG. 1, on an enlarged scale;

FIG. 3 is a view from the top of a housing for data processing component shown in FIG. 1;

FIG. 4 is a view from the bottom of a housing for data processing component shown in FIG. 1;

FIG. 5 is a view from the right side of a housing for data processing component shown in FIG. 1; and,

FIG. 6 is a view from the left side of a housing for data processing component shown in FIG. 1.

FIGS. 3-6 are shown on enlarged scales. The rear view is plain and unornamented.
